DYEING-MACHINE.

No. 887,511.

Specification of Letters Patent.

Patented May 12, 1908.

Application filed July 18, 1907. Serial No. 384,425.

To all whom it may concern:

Be it known that we, JESSE M. PAYNE, a citizen of the United States, residing at Phoenix city, county of Lee, Alabama, and 5 GEORGE G. WALLACE, a citizen of the United States, residing at Girard, in the county of Russell and State of Alabama, have invented certain new and useful Improvements in Dyeing-Machines; and we do declare the following to be a full, clear, and exact description of the invention, such as will enable others skilled in the art to which it appertains to make and use the same.

This invention has relation to new and 15 useful improvements in dyeing machines, and has for its object the production of a simple and economical machine of this character by means of which the dyeing of cotton, yarn or other like material may be accomplished in a thorough and expeditious manner and with a minimum of labor.

In the accompanying drawings, in which like parts are designated by like characters of reference, throughout the several views,— 25 Figure 1 is an end view of the machine as applied in operative position; Fig. 2 is a plan view, part of the upper or removable section of the jacket broken away to more advantageously illustrate the invention; Fig. 3 is 30 a cross sectional view on the line 3—3 of Fig. 2, looking in the direction indicated by the arrows.

Referring to the drawings for a more particular description of the invention, the numeral 1 indicates an open vat or box for the dye.

In carrying out the invention a hollow jacket is provided which comprises a lower stationary member or section 2 of preferably 40 semi-circular form in cross section mounted on suitable legs 3 and arranged in the vat or box. Said section or member is provided at its edges with outwardly extending flanges 4 and at each end on its inner face with two 45 inwardly extending spaced flanges or ribs 5, the function of which will be shown. The upper member or section 6 is also of preferably semi-circular form in cross section to correspond with the lower section, and is 50 provided at its side edges with outwardly extending flanges 7, and also at each end and on its inner face with two inwardly extending spaced flanges 8 to register with the flanges 5 of the lower or stationary section when 55 placed in position.

In the drawings, we have shown two different methods of securing the upper section of the jacket in removable position to the lower or stationary section. One of these methods consists in employing a simple 60 clamp 9 of substantially U-shaped form, the side flanges or members 10 of which are adapted to clamp the outer faces of the outwardly extending flanges of the jacket sections. The other method that may be employed to fasten the upper section of the jacket consists in providing the outwardly extending flanges of the lower or stationary section with a longitudinal series of recesses 11, and the outwardly extending flanges 7 of 70 the other section with corresponding recesses 12 to register therewith when arranged in proper position. Eye bolts 13 are hingedly connected at their ends to the lower or stationary section in position to be swung 75 into the recesses of the outwardly extending flanges of said sections and are provided at their threaded ends with washers 14 adapted to clamp the upper faces of the outwardly extending flanges of the upper section, which 80 engagement is made secure by nuts 15, disposed or arranged on said threaded ends.

We will now describe a form of warper beam preferably employed in carrying out the invention. This beam comprises a supporting shaft or rod 16 having outwardly extending stop flanges or collars 17 at suitable points from its ends and provided at each end a suitable distance outward of said stop flanges or collars with a thread 18. Beam 90 heads 19 of circular form are arranged on the ends of said supporting shaft or rod and are provided with central reduced portions 20 on the inner faces, adapted to abut or engage the stop flanges or collars 17, whereby they are 95 held against inward displacement. Nuts 21 are screwed on the threads of said supporting shaft or rod against the outer faces of the beam heads to secure them in removable position. Each of the central reduced portions 100 20 of said heads is provided at its periphery or outer surface with a circular series of sockets or recesses 22, to receive the ends of a series of yarn holding rods or members 23 adapted to be arranged between said heads. 105 The ends of said supporting shaft or rod project beyond the beam heads and constitute handles 24 for carrying the warper beam from place to place.

In practice the warper beam is taken to the 110

beamer, placed in proper position and supplied with white yarn of any description, which is wound around the yarn holding rods or members 23. This done, the warper beam 5 is carried to the dye house and placed in the lower or stationary section of the jacket, the enlarged portions of the warper beam heads fitting between the inwardly extending spaced flanges 5 of said section. The upper section 10 is then placed over the warper beam and fastened in removable position to the lower section by either of the methods described, or, in fact, it may be fastened in any other suitable manner.

15 We will now describe an arrangement for dyeing the yarn. A horizontal pipe 25 communicates at one end with the vat or box 1, and at its opposite end with one portion of a suitable pump 26. A feed tube 27 is arranged in one of the warper beam heads at a point to communicate with the space surrounded by the yarn on the yarn holding rods or members. A pipe 28 has one end secured to the outer end of said tube and communicates 20 at its opposite end with a portion of said pump. A pipe 29 communicates at one end with the lower section of the jacket and has a horizontal portion 30 arranged to extend over the box or vat and a vertical portion 31 connected with said pipe 25 at a suitable point. A vertically disposed pipe 32 is arranged between the horizontal portion 30 of said pipe 29 and the pipe 28. A vertically disposed pipe 33 also is arranged as a connection between pipes 25 and 28 preferably at a point 35 inwardly of pipe 32. Pipes 32 and 33 are provided at suitable points with valves 34 and 35, respectively, pipe 28 preferably at a point between said pipes 32 and 33 with a valve 36, the vertical portion of pipe 29 with a valve 37 at a suitable point, and pipe 25 also with a valve 38, preferably at a point inward of pipe 33. A threaded plug 39 is secured in a corresponding aperture or opening 40 formed in the upper jacket member 6, the purpose of which will be disclosed.

In practice we first close valves 35, 34 and 37 and open valves 36 and 38. We then unscrew the plug from position and throw the 50 pump in operation which draws the dye liquor from the vat or box 1 through the pipe 25 and pump it into the space surrounded by the yarn, on the yarn holding rods of the warper beam through the pipe and feed tube 55 28 and 27, respectively. The pump is kept in operation until the dye has reached the desired level in the jacket when the plug, 39, is again screwed in position. After the desired pressure has been obtained, valve 38 is 60 closed and valve 37 opened. The dye is then passed through pipe 25 and thence through pipe 28 and the feed tube into the space surrounded by the yarn on the warper beam through the yarn into the jacket and out of 65 the jacket through pipe 29 back to pipe 25,

whereby a complete circulation of the dye through the yarn is established. This operation is continued as long as desired, and should the pressure drop from any cause and more dye be required, valve 38 is opened to 70 draw more dye from the vat, and after the desired pressure has been secured, said valve is again closed. To reverse the flow of the dye, valves 36, 37 and 38 are closed and valves 35 and 34 opened, when the dye liquor 75 is drawn out of the machine through pipe 28-33-25 to the pump and from the pump is forced through pipes 28-32 and 29 to the interior of the jacket.

From the arrangement disclosed it will be 80 seen that a continuous circulation of the dye, either first through the yarn and thence out of the jacket, or first through the jacket and thence through the yarn, may be secured to 85 secure a uniform dyeing of the yarn, and that a certain pressure may be maintained at all times.

From the foregoing description, taken in connection with the accompanying drawings, the construction and operation of the 90 invention will be readily understood without requiring a more extended explanation.

Various changes in the form, proportion and the minor details of construction may be resorted to without departing from the principle or sacrificing any of the advantages of 95 this invention.

Having described our invention, we claim:—

1. In a dyeing machine, the combination 100 of an open vat, a jacket arranged within the vat, said jacket comprising a lower stationary section and a removable upper section, a warper beam comprising a longitudinally disposed supporting rod, beam heads adapted to be arranged at the ends of said rod and a plurality of yarn holding members adapted to be arranged between said heads arranged in said jacket, with means whereby a continuous circulation of dye through the jacket 110 may be established.

2. In a dyeing machine, the combination of an open vat, a lower stationary member having outwardly extending side flanges and two inwardly extending spaced flanges at 115 each end arranged therein, a warper beam comprising beam heads adapted to be fitted between the inwardly extending flanges of said lower member and a circular series of spaced members arranged between the beam 120 heads, an upper jacket member adapted to be arranged over said stationary member having side flanges to correspond therewith and inwardly extending spaced flanges at each end to correspond with and register with the 125 inwardly extending flanges of the lower member, means for removably securing said upper section member in position, and means whereby a continuous circulation of dye through the jacket may be established. 130

- 189 3. In a dyeing machine, the combination of an open vat, a hollow jacket comprising two separable sections arranged therein, a warper beam comprising beam heads and a plurality of spaced yarn holding members arranged between the heads adapted to be arranged in said jacket, means communicating at two points with the interior of the jacket whereby a continuous circulation of dye through the jacket may be established, means for reversing the direction of flow of the dye, and valves and connections being so arranged as to permit of a regulation of the pressure from the dye liquor within said jacket.
4. In a dyeing machine, the combination of a hollow jacket comprising two separable sections each having outwardly extending side flanges and two inwardly extending spaced flanges on its inner face at each end, a warper beam comprising a longitudinal supporting member, beam heads arranged near the ends of said rods and adapted to be received between the inwardly extending flanges of the jacket sections, and a circular series of spaced yarn holding members arranged between the beam heads, with means whereby a continuous circulation of dye through the jacket may be established.
5. In a dyeing machine, the combination with an open vat, a hollow jacket of circular form in cross section comprising upper and lower separable sections each having outwardly extending side flanges and two inwardly extending spaced flanges on its inner
- face at each end, the inwardly extending flanges at either end of one section being adapted to register with the flanges at the adjacent end of the other section, a longitudinally disposed supporting member, beam heads adapted to be received between the inwardly extending flanges of said jacket sections and having reduced portions on their inner faces, each having a circular series of sockets or recesses in one face, and a plurality of yarn supporting members arranged between said beam heads and having their ends received by the sockets or recesses in the reduced portions thereof with means communicating with the interior of the jacket at two points for effecting a continuous circulation of the dye through the jacket.
6. In a dyeing machine, the combination of an open vat, a hollow jacket comprising two separable sections arranged therein, a warper beam arranged in the jacket, means communicating at one point with the vat and at two points with the interior of the jacket, whereby a circulation of dye through the jacket in one direction may be established, and means for reversing the direction of flow of the dye.

In testimony whereof we have hereunto set our hands in presence of two subscribing witnesses.
